UNITED STATES PATENT OFFICE

2,065,811

FINGER RING

Earl Kiff, Attleboro, Mass., assignor to L. G. Balfour Company, a corporation of Massachusetts

Application September 19, 1936, Serial No. 101,679

9 Claims. (Cl. 63—15)

This invention relates to an article of jewelry, such as for example a finger ring; and has for one of its objects the provision of a gem or stone with an emblem mounted above the stone in such a manner that the stone is protected against being struck in such a manner as to injure or break the stone.

Another object of the invention is the provision of a device of this character in which the stone or gem is positively seated to prevent rattling or moving about beneath the emblem.

Another object of the invention is to securely hold the stone or gem and the emblem in separate seats so that the desired amount of holding pressure may be exerted upon each separately.

Another object of the invention is the provision of an arrangement which will permit of many and various different designs of emblems at a low cost of manufacture.

A further object of the invention is the seating of the stone or gem in a holding device completely independent of the base or ring shank upon which the holding device is attached or mounted as a base.

With these and other objects in view, the invention consists of certain novel features of construction, as will be more fully described, and particularly pointed out in the appended claims.

In the accompanying drawing:

Fig. 1 is a perspective view of a completed ring formed in accordance with my invention;

Fig. 2 is a view similar to Fig. 1 with the emblem member removed from mounted position;

Fig. 3 is a view similar to Figs. 1 and 2 with both the emblem member and gem or stone member removed from mounted position;

Fig. 4 is a perspective view of the emblem member;

Fig. 5 is a top plan view of the stone or gem member;

Fig. 6 is a sectional view through the ring shank and its holding device;

Fig. 7 is a view similar to Fig. 6 with the gem or stone member mounted in position;

Fig. 8 is a view similar to Fig. 7 but showing additionally the emblem member of Fig. 4 in mounted position;

Fig. 9 is a sectional view on line 9—9 of Fig. 8;

Fig. 10 is a view similar to Fig. 7 showing a somewhat modified arrangement of stone and emblem member seat with the stone in mounted position;

Fig. 11 is a view similar to Fig. 10 with the emblem member in mounted position;

Fig. 12 is a top plan view of a modified form of emblem mounting seat with the emblem in position;

Fig. 13 is a top plan view of the structure

of Fig. 12, with the emblem and stone members removed;

Fig. 14 is a sectional view on line 14—14 of Fig. 13.

In the use of stone protected articles of jewelry such as finger rings where there is an emblem member which is mounted over a gem or stone member with piercings in the emblem member so that the stone may be viewed through the piercings and forms a background for the emblem, it frequently occurs that the stone will rattle or move, which is undesirable. It also sometimes occurs that the stones are of varying thicknesses and some compensation has to be made in order to accommodate the stones of these varying thicknesses; and in order to avoid both of these undesirable results, I have provided a holding member having a seat for the gem therein in which the gem is individually and securely held, and I provide another seat for the superimposed emblem so that this emblem will cover over the edge of the stone and be flush with the outer surface of the holding device, in which position it is securely held to provide an attractive appearance; and the following is a more detailed description of the present embodiment of this invention, illustrating the preferred means by which these advantageous results may be accomplished:

With reference to the drawing, 15 designates the shank of the ring or other article of jewelry which forms the base and mounting portion for the holding device designated as 16 which is formed separate from the shank 15 and soldered to a flat base portion 17 provided on the top of the shank, although if practical, so far as the invention is concerned, these parts 15 and 16 could be made in one piece.

A holding device 16 is provided with a gem seat 18 of a bevel formation for the reception of a gem 19 having a bevel edge 20 to fit against this seat 18. The raised periphery or edge portion 21 of this seat 18 is then peened over as at 22 in Fig. 7, to hold the gem 19 snugly and securely in and against its seat 18. A larger recess portion 24 provides a separate and independent seat 23 for an emblem member 25. This emblem member is somewhat arched in construction and of a shape substantially corresponding to the shape of the upper surface 26 of the stone 19 so as to closely follow the same and be either spaced therefrom slightly or in close contact therewith to prevent the accumulation of dirt or foreign matter between the emblem 25 and the gem 19. This emblem is pierced or cut out as at 27 so that the gem or stone 19 may be viewed therethrough and provides a background for the emblem as it is viewed from the top of the ring. The thickness of the emblem member is such that in the showings of Figs. 1 and 8, the upper

edge 28 of the holding device is substantially flush with the upper surface 29 of the emblem member and thus both the edge of the stone and the emblem member are protected against injury to their edges.

This emblem member may be held in this position on its separate seat 23 by any suitable means. I have illustrated in Figs. 1 to 9 inclusive, pins 30 as secured to the back of the emblem member 25 and extending through the stone 19 and riveted over as at 31 in back of the stone. However, other various means may be provided for holding this emblem member on its separate seat, such for instance as the peening or rolling in of the edge portion 32 of the holding device 16 and the rolling over of this edge portion as at 33 in Fig. 11 to hold the emblem member in position. In this case, the holding of the emblem member is entirely independent of the stone and the stone and emblem member are held separately and firmly so that regardless of the thickness of the stone each is held against rattling. In this case, the edge portion 33 in being peened over about the entire edge of the stone is thinned down sufficiently so that its surface merges with that of the emblem member and is substantially flush therewith.

In some cases, instead of having a continuous annular seat in the holding device about the stone the seat for the emblem member may be in three sections as 35, 36 and 37 and the emblem member 38 is provided with three fingers 39, 40 and 41 spaced correspondingly with the spacing of the seats 35, 36 and 37, in which case this emblem member is positioned above the stone and the edge portions 42, of these seats, are rolled over the fingers 39, 40 and 41 so as to hold the emblem member in mounted position above the stone.

40 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat.

2. An article of jewelry comprising a member provided with a gem mounting seat inwardly from the outer surface thereof, and a second seat located outwardly of the gem seat and inwardly from the outer surface thereof, a gem on said gem seat with portions thereof extending over the edges of the gem to hold the same thereon, an emblem member seated on said second seat and of a thickness to be substantially flush with the outer surface of the device, and means to hold said emblem member on said second seat.

3. An article of jewelry comprising a base portion provided with a holding device having a gem mounting seat in the holding device inwardly from the outer surface thereof, and a second

seat located outwardly of the gem seat, a gem on said gem seat with the edge of the device about the seat rolled over the edge of the gem, an emblem member seated on said second seat, and means to hold said emblem member on said second seat.

4. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat comprising pins to extend through the stone.

5. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat comprising portions about the second seat to extend over the edges of the emblem member and hold the same in position.

6. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat comprising portions about the entire periphery of the second seat to extend over the edges of the emblem member and hold the same in position.

7. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat, comprising portions spaced about the second seat to extend over the edges of the emblem member and hold the same in position.

8. An article of jewelry comprising a base portion, a separate holding device attached thereto provided with a gem mounting seat in the holding device inwardly from the outer surface thereof and independent of the base, and a second seat located outwardly of the gem seat, a gem on said gem seat, means for holding the gem on the seat, an emblem member seated on said second seat, and means to hold said emblem member on said second seat.

9. An article of jewelry comprising a member provided with a gem mounting seat inwardly from the outer surface thereof, and a second seat located outwardly of the gem seat, a gem on said gem seat with portions thereof extending over the edges of the gem to hold the gem thereon, and an emblem member seated on said second seat, and means to hold said emblem member on said second seat, said member having an opening beneath the gem.

EARL KIFF.
